UNITED STATES PATENT OFFICE.

EDWARD A. ROEHL, OF ST. PAUL, MINNESOTA.

METHOD OF MAKING PISTON-RINGS.

1,322,056.

Specification of Letters Patent. Patented Nov. 18, 1919.

Application filed August 6, 1917. Serial No. 184,776.

To all whom it may concern:

Be it known that I, EDWARD A. ROEHL, a citizen of the United States, and a resident of St. Paul, in the county of Ramsey and 5 State of Minnesota, have invented certain new and useful Improvements in Methods of Making Piston-Rings, of which the following is a specification.

The object of my invention is to provide 10 an improved method, with its incidental product, for forming a piston ring for internal combustion engines and the like.

With this and incidental objects in view the invention consists of certain novel 15 methods and sequences of operations, the essential elements of which are hereinafter described with reference to the drawing which accompanies and forms a part of this specification.

20 In the drawing Figure 1 is a side elevation of my improved piston ring; Fig. 2 is a plan view of the same, and Fig. 3 is a detail of the lap portion formed by an alternate method. Fig. 4 is a side elevation of a helical spring having a considerable number of convolutions and showing how the spring is 25 to be cut into individual springs for forming the piston rings.

My invention contemplates broadly the 30 forming of a piston ring that shall have two complete convolutions to more thoroughly seal the engine cylinder in which it is used than does the common type of ring.

While piston rings have been made heretofore having two or more convolutions, I believe that my method of producing the ring 35 is entirely new.

When the ring is to be made of steel or other suitable material capable of being 40 formed, I prefer to form a helical spring having a large number of convolutions as shown in Fig. 4 and then cut this spring into a number of individual springs, each having two complete convolutions.

45 With the individual springs so cut each is placed in a die and by exerting pressure upwardly in the direction of the arrow 1, Fig. 1, and downwardly as indicated by the arrow 2 with the portions 3 and 4 of the ring 50 maintained in a horizontal position, a double bend is formed with an angle at 5 fitting the angle at which the end 6 of the ring has been cut off, and with the angle at 7 fitting the similar angle at which the end 8 has 55 been cut off.

When making rings of metal of this type, the method described is extremely low in manufacturing cost as it is only necessary to form up the springs, make the individual cuts at the proper angle, and then strike the 60 individual ring so formed in a die, thus completing the piston ring, which may be turned or ground later or not as desired.

When a cast iron ring is desired I form my improved ring in a somewhat different 65 manner.

Two individual rings are turned of cast iron in the ordinary manner and each of the rings is then cut on an angle, as shown in Fig. 3. 70

After the rings have been so formed they are positioned with the ends as shown in Fig. 3, and a portion 9 of each of the rings is then welded together thus forming one complete ring having two convolutions. 75

It is apparent that the lap at 9 may be of any suitable length, the new feature of this method being the welding of two such rings at their opposite extremities so as to form thereby a single ring having two convolu- 80 tions.

While I have described my invention and illustrated it in two particular designs, I do not wish it understood that I limit myself to these methods, as it is evident that the application of my invention may be varied in many ways within the scope of the following 85 claims.

Claims:

1. The method of forming piston rings 90 comprising the forming of a rod of rectangular section into a helical spring, cutting the helical spring into individual springs having two convolutions, and forming the central portion of the individual spring in a 95 die so as to bring the outer ends of the helical spring into two respective parallel planes.

2. The method of forming piston rings comprising the forming of a rod of rectangular section into a helical spring, cutting 100 the spring by diagonal cuts into individual springs, having two convolutions, and forming the central portion of the individual springs transversely between the diagonally cut ends to produce a piston ring having its 105 edges parallel.

EDWARD A. ROEHL.
